Fig. 1

Fig. 1 is a front elevational view of a tiltable bottle showing our new design;

Fig. 2 is a view similar to Fig. 1, but taken at right angles to the position shown in the said figure; and

Fig. 3 is a plan view of the bottom of the tiltable bottom.

Fig. 4 is an enlarged fragmentary detailed view of the criss-cross surface ornamentation shown in Figs. 1 and 2.

The rear and side not shown are the same as the front and side, respectively, shown.

We claim:

The ornamental design for a tiltable bottle, substantially as shown and described.
